(**) Term: **14 Years**

(57) **CLAIM**
The ornamental design for a racking for solar thermal collector, as shown and described.

(21) Appl. No.: **29/419,317**

DESCRIPTION

(22) Filed: **Apr. 26, 2012**

FIG. 1 is a front perspective view of a racking for solar thermal collector showing my new design;

(51) LOC (10) Cl. **13-02**

FIG. 2 is a front view thereof;

(52) U.S. Cl.

FIG. 3 is a top view thereof;

USPC **D13/102**

FIG. 4 is a left side view thereof;

(58) **Field of Classification Search**

FIG. 5 is a right side view thereof;

USPC D13/102, 101, 107, 184, 199; D25/57,

D25/61, 199; 52/74, 77, 78; 126/569, 571,

126/577, 600, 603, 605, 606, 608, 704;

136/243-246, 251; 320/101

FIG. 6 is a back view thereof;

See application file for complete search history.

FIG. 7 is an enlarged fragmental view thereof, as indicated by
